Inventor:

George Bohner,

by Robert Burns Atty.

UNITED STATES PATENT OFFICE.

GEORGE BOHNER, OF CHICAGO, ILLINOIS.

DESIGN FOR A LAMP-FIXTURE.

SPECIFICATION forming part of Design No. 30,903, dated May 30, 1899.

Application filed March 21, 1899. Serial No. 709,980. Term of patent 3½ years.

To all whom it may concern:

Be it known that I, GEORGE BOHNER, a citizen of the United States, residing at Chicago, in the county of Cook and State of Illinois, 5 have invented and produced a new and original Design for Lamp-Fixtures; and I do hereby declare the following to be a full, clear, and exact description of the same, reference being had to the accompanying drawing, forming a part of this specification.

The present invention relates to a new and original design for lamp-fixtures, of which the following is a detailed description, reference being had to the accompanying drawing, forming a part of this specification, and which drawing shows the fixture in elevation.

The fixture consists of a vertical member 1, having an intermediate lateral neck 2, to which is attached the upper portion of the 20 horizontally-extending "return-bend" member 3, having the particular shape shown in the drawing.

The member 1 carries at its lower end the curved or ovaliform member 4, that is interspaced to constitute two ends to said member, the upper and free end 5 of which is substantially horizontal and in line with the lower portion of the return-bend member 3, while the lower end 6 of such curved or ovaliform member 4 is curved upwardly and provided with a vertically-extending nipple 7.

Having thus fully described my said invention, what I claim as new, and desire to secure by Letters Patent, is—

The design for a lamp-fixture, as herein shown and described.

In testimony whereof witness my hand this 14th day of March, 1899.

GEORGE BOHNER.

In presence of—

ROBERT BURNS,
M. H. HOLMES.
